METHOD OF MAKING MUFFLERS AND
THE LIKEClarence M. Buck, Jackson, Mich., assignor to
Hayes Industries, Inc., Jackson, Mich., a cor-
poration of Michigan

Application April 29, 1940, Serial No. 332,173

2 Claims. (Cl. 29—157)

The present invention relates to mufflers and to a method of making the same and particularly to a muffler produced by the apparatus disclosed in my co-pending application Serial No. 332,174 filed April 29, 1940.

Before the employment of outwardly projecting louvers on muffler tubes, it was the practice to provide baffles having central openings through which the muffler tube was disposed and then to spot weld the baffles onto the tubes to secure them in position. However, since the employment of louvers having projecting portions came into use, it was necessary to make the opening in the louvers of such size as to clear the louvers. Since the openings in the baffles were of such size as to prevent a snug fit on the portion of the tube not provided with louvers, it was then necessary to crimp the baffles in order to bring the central opening down to a size whereby the baffles could be secured to the tube by some convenient method such as spot welding. The crimping operation is unsatisfactory as such and is expensive. Particularly unsatisfactory is the misalignment of the baffles that results in making difficult subsequent telescoping over the baffles of an outer shell or tube. Another practice has been to roll ridges in sheet metal before rolling it into muffler tubes and then mounting baffles on the ridges on the tubes. An example of this practice is disclosed in Patent No. 1,878,424 to Oldberg. This method is unsatisfactory because in lock seaming the muffler tubes, the ridges are crushed. According to the present invention, the tube has limited lengths thereof expanded into peripheral contact with enlarged openings in the baffles. As an additional refinement, a bead is struck up from the expanded portions of the tube on each side of the baffles to prevent axial movement of the baffles with respect to the tube. With the baffles thus assembled on a tube, an alignment of the baffles is obtained which makes the telescoping of an outer shell or tube onto the baffles a simple matter and a muffler section is obtained wherein there is a degree of peripheral engagement between the baffles and the inner and outer tubes not possible when employing prior assembling practices.

An object of the invention is to provide a muffler having a tube provided with an external annular ridge supporting thereon a baffle.

Another object of the invention is to provide a muffler having a tube provided with an external annular ridge with a baffle supported there-

on and a bead at each side of the baffle for preventing axial movement of the baffle with respect to their tubes.

A further object of the invention is to provide 5 a muffler having a baffle between inner and outer tubes provided by an outwardly expanded portion in the inner tube and an inwardly directed portion in the outer tube, the two portions being in peripheral engagement.

10 A still further object of the invention is to provide a method for securing baffles to tubes in mufflers or the like which comprises outwardly expanding an annular ridge from the material of the tube into engagement with a baffle disposed in a desired relation on the tube.

A still further object of the invention is to provide a method of securing a baffle to a tube which comprises expanding outwardly an annular ridge from the material of the tube into engagement with a baffle in the desired relation on the tube and expanding from the expanded portion a bead on each side of the baffle to prevent axial movement thereof with respect to the tube.

25 A still further object of the invention is to provide a baffle between an inner and an outer tube in a muffler by forming in the outer tube an annular ring inwardly of the surface of the tube, disposing an inner tube within the outer tube and radially expanding an annular ring from the material of the inner tube into peripheral engagement with the inwardly extending ring of the outer tube.

30 A still further object of the invention is to provide a muffler tube and the method of making the same wherein there is an integral, uncrushed ridge including a lock seam.

These and other objects will be apparent from the following specification when taken with the 35 accompanying drawings, in which:

Fig. 1 is a vertical section of a muffler disclosing the present invention,

Fig. 2 is section on the line II—II of Fig. 1,
Fig. 3 is a vertical section of a portion of a 40 muffler disclosing the invention,

Fig. 4 is a vertical section of apparatus for expanding a tube onto a baffle according to the present invention,

Fig. 5 is a partial section taken through a 45 muffler tube and ridge forming apparatus at the apex of the ridge, showing the arrangement for providing a smooth external periphery for the ridge notwithstanding the lock seam in the tube,

Fig. 6 is a vertical section of another muffler, and

Fig. 7 is a partial section showing an enlarged scale a baffle attached to a tube.

Referring particularly to the drawings, there is disclosed in Fig. 1 a muffler according to the present invention. The muffler consists of a through inner tube 1, a tube 2 surrounding the through tube 1, and an outer shell 3. The ends of the muffler are provided with heads 4 which do not form a part of the present invention. A baffle 5 forms a partition between the through tube 1 and the tube 2. The through tube 1 is provided with a plurality of louvers 6 which are provided with portions projecting outwardly from the tube 1 and as shown particularly in the drawings. Because of these outward projections, it is necessary that the opening in the baffle 5 through which the tube 1 is projected be of a larger diameter than the diameter of the tube itself in order to clear the projections of the louvers 6. The previous practice was to crimp the baffle 5 onto the tube 1. However, according to the present invention, the inner tube 1 has a limited length thereof beneath the baffle 5 expanded into a ridge 7 into peripheral engagement with the baffle 5.

Referring to the drawings, it will be observed that the baffle 5 is provided at the portion in contact with the ridge 7 with an axially extending flange 8. At each side of the flange 8 is an expanded bead 9, annular in configuration and retaining the baffle 5 against axial movement with respect to the tube 1. The tube 1 and the flange 8 may be spot welded together or not as desired.

In Fig. 2 is shown another application of the invention wherein a through tube 15 provided with louvers 16 has associated with it an outer tube 17. In the portion of the through tube 15 disclosed are three radially expanded ridges 18 corresponding to the ridge 7 of Fig. 1. The ridges 18 are expanded from the metal of the tube 15 into peripheral engagement with the flanges 19 of baffles 20 and the baffles 20 are held against axial movement with respect to the tube 15 by integral expanded beads 21 at each side of the flanges 19. When the baffles 20 have been secured to the tube 15, the outer tube 17 is telescoped onto the baffles 20 and secured thereto in some suitable manner as by spot welding.

Another form of the invention is disclosed in Figs. 1 and 3 wherein a baffle is formed from the material of the tubes 1 and 2. The tube 2 has a portion thereof necked down to provide an annular ring 25 of considerably less diameter than the diameter of the tube 2. In Fig. 3 is shown more particularly the way in which the tube 2 is necked down. The excess material of the tube 2 over that which is included in the ring 25 is utilized in folds 26. The necking down of the tube 2 may be accomplished in a manner specifically disclosed in the co-pending application of Beecher B. Cary, Serial No. 221,474, filed July 27, 1938.

In the portion of the tube 1 directly opposite the ring 25 there is expanded an annular ridge 27 similar to the ridge 7, with the exception that it is not provided with the annular beads 9. The ridge 27 is expanded into peripheral engagement with the ring 25 so as to form with the portion of the tube 2 necked down to form the ring 25, a baffle providing with the baffle 5 and the tubes 1 and 2 a high frequency resonance chamber 28.

The apparatus for expanding the ridges in the inner tube to support a surrounding baffle is disclosed particularly in my copending application, executed on even date herewith. The apparatus

is shown in Fig. 4 of the drawings in simplified form for the purposes of the present disclosure. Referring particularly to Fig. 4, baffles 30 to be secured to a tube are disposed in assembled relation with the tube 31 and the tube 31 is secured in fixed position by means of annular clamping members 32. As shown more fully in my aforesaid co-pending application, the members 32 are in the form of two halves permitting opening of the halves for placing the baffles 30 and for removing the tube 31 having the baffles 30 secured thereto. In the use of the structure disclosed in Fig. 4, the halves of the clamping members 32 are separated to permit placement of baffles 30. The tube 31 is then disposed through the openings in the baffles 30 and the halves of the clamping members 32 brought together to lock the baffles 30 in a predetermined relation with respect to the tube 31. As shown in the drawings, the clamping members 32 when in assembled relation with the tube 31 limit the length of the ridges which are to be expanded. When the clamping members 32 have been clamped as aforesaid, a quill 33 is disposed in the tube 31, the quill 33 being provided internally with a mandrel 34 having therein camming surfaces 35 for engaging with follower members 36 which comprise portions of radially movable segmental dies 37. It will be understood that there are a plurality of dies 37 circumferentially arranged around those portions of the quill 33 at which ridges are to be expanded. The follower portions 36 of the dies 37 project inwardly through openings 38 in the quill 33. The dies 37 as well as the quill and mandrel structure and the structure for actuating the same are more particularly disclosed in my aforesaid co-pending application.

While the quill 33 is maintained stationary, the mandrel 34 is drawn longitudinally (to the left in Fig 4) with respect to the quill 33 to cause the camming surfaces 35 to cam the dies 37 radially outwardly into engagement with the tube 31 to form annular ridges 39. Backing up rings 40 are provided for the flanges 41 of the baffles 30. The rings 40 are supported with respect to and move with the clamping members 32 and like the clamping members 32 are in two halves. The internal diameter of the backing up rings 40 should be slightly greater than the finished external diameter of the flanges 41 for the reason that as the dies 37 radially expand the ridges 39 and then withdraw, the resiliency of the metal of the tube 31 will result in a final diameter of the ridges 39 which is slightly less than the maximum diameter during the expanding, and unless the diameter of the rings 40 is as stated, a good peripheral engagement of the ridges 39 with the flanges 41 will not be obtained. Each of the dies 37 is acted upon by a cantilever leaf spring 42, each of which moves a die 37 radially inwardly when the mandrel 34 is moved inwardly with respect to the quill 33 after the expanding operation has been completed. It will be observed that the dies 37 are provided with beads 43 for providing corresponding beads 44 in the ridges 39 for the purpose of supporting the baffle 30 against axial movement with respect to the tube 31 as has been hereinabove explained with respect to the structures disclosed in Figs. 1 and 2.

An important function of the clamping members 32, together with the backing up rings 40 is to support the baffles 30 in a predetermined alignment so that the baffles when they are secured to the tube passing through them may be readily telescopically assembled in an outer

tube. While in the form of the invention disclosed, the axial alignment of the baffles 30 is controlled by the flanges 41 thereof, abutting against the backing up rings 40, it will be appreciated that the baffles 30 themselves may be accurately formed to close limits and therefore the outer peripheries thereof will be in true axial alignment when the flanges 41 are maintained in true axial alignment. This alignment results in simplifying the telescoping of an outer tube over baffles and provides a muffler section having an accurate peripheral engagement between the baffles and tube surrounding them.

While in Fig. 1, there have been disclosed beads 9, raised from the ridges 7 for preventing axial movement of the baffles 5 with respect to the tube 1, it will be appreciated that in the place of the ridges 9, there may be provided a series of radially extending, circumferentially spaced, disconnected projections without departing from the spirit and scope of the invention. Furthermore, it will be appreciated that while the baffles have been disclosed as having central openings, the openings through the baffles may be off-center. A case where the openings to baffles would be off-center is where the baffles are elliptically shaped, for instance where a retroverted flow type of tube is employed.

One feature of the present invention which is not readily obvious is the fact that the point at which the baffles are secured to the through tube remains cooler during operation than other portions of the through tube. The reason for this apparently is because the ridges supporting the baffle provide, with respect to the interior of the through tube, a channel past which the exhaust gases from the internal combustion engine with which the muffler is used flow. As the gases flow by these channels they draw a vacuum of some unknown degree in the channels which results in insulating the outer sides of the ridges from the hot gases. Also the outer sides of the ridges to which the baffles are connected are out of the main paths of the hot exhaust gases. It is believed that it is the combination of these two factors which results in the outer sides of the baffle supporting ridges remaining cooler than the rest of the inner tube in which the ridges are formed. As a result the life of these portions of the inner tube is prolonged and since it is the points of connection of baffles to the inner tube which fails first in service, the life of the muffler is considerably prolonged.

As pointed out hereinabove, one of the difficulties encountered in rolling baffle supporting ridges in sheet metal before it has been formed into tubes, resides in the fact that in lock seaming the edges of the metal in forming the tubes, the ridges are crushed. The present invention not only overcomes this difficulty but also provides a smooth and continuous surface at the periphery of each ridge by disposing the lock seam inwardly of the surface of each ridge. A section of a muffler tube and the arrangement for disposing the lock seam inwardly of the peripheral surface of a ridge is disclosed in Fig. 5. As shown, the tube 31 is supported on the quill 33 surrounding the mandrel 34 and dies 37, have been cammed radially, through the followers 36, to expand a portion of the tube 31 into a ridge 39, against a backing ring 40. According to the invention, one of the dies 37 is provided with an axially extending recess 50 for receiving the lock seam 51 in the tube 31. Prior to forming the ridge 39 when the tube 31 is assembled with re-

spect to the quill 33, the recess 50 is disposed opposite the lock seam 51. It will be understood that prior to the radial movement of the die 37 to expand the ridge 39, the lock seam 51 will be at least in part raised above the exterior surface of the tube 31, as is usual from ordinary lock-seaming operations in the formation of lock seamed tubes from sheet metal. When the dies 37 are moved outwardly, the lock seam 51, as the result of the resisting action exerted by the backing ring 40 is moved into the axial recess 50 and the ridge 39 is provided with a continuous smooth exterior surface. Thus there is provided a tube having an integral ridge which is not crushed at the lock seam and the leakage which occurred between the baffle and the crushed ridge of the prior practice is eliminated.

Another use to which the invention may be put is disclosed in Fig. 6. A muffler through tube 20 60 is provided with a plurality of baffles 61, secured thereto according to the present invention. The through tube 60 is also provided with a plurality of baffles 62, also secured according to the present invention. It will be observed that the external diameter of the baffles 61 is substantially less than that of the baffles 62 and that an intermediate tube 63 is telescoped over the baffles 61 and an outer shell 64 is telescoped over the baffles 62. Thus, while in the form of the invention disclosed in Fig. 2, the baffles 20 were of uniform size to permit the alignment thereof for telescopically receiving a tube, the baffles in Fig. 6 are of different sizes but nevertheless are aligned in groups according to sizes to permit the telescoping thereover of tubes of different diameters according to a predetermined muffler design.

It will be observed that the baffles 61 and one of the baffles 62 are supported on the ridges 65, corresponding to the ridges 18 disclosed in Fig. 2, and that the other baffle 62 is not supported on a ridge, but is maintained against longitudinal displacement by expanded beads 66 corresponding to the beads 21 disclosed in Fig. 2.

It will be appreciated that while the invention has been illustrated as applied to the securing of baffles to tubes wherein the portions of the tube to which the baffles are secured are of less effective diameter than the extreme diameter of portions of the tube having outwardly projecting louver portions over which the baffles must pass in assembling, the invention is equally applicable to constructions wherein the tube has no externally projecting louvers and therefore no substantial baffle supporting ridges are required. In other words, the feature of the invention which provides an exact axial alignment of the baffles to permit them to be assembled telescopically in an outer tube after being secured to an inner tube may be used with or without the baffle supporting ridge expanded from the inner tube. The right baffle 62 in Fig. 6 illustrates the manner of securing a baffle where there are no louvers over which a baffle must be passed in assembling, that is, the case where it is not necessary to radially expand ridges of substantial height to support the baffles, but where the tube supporting the baffles is expanded only sufficiently to clamp the baffles. It will be observed that as shown in Fig. 6, the end portion 67 of the through tube 60 is not provided with outwardly projecting louvers and therefore the end baffle 62 may be readily slipped over the end portion 67, even though the diameter of the opening in the end baffle 62 is only very slightly greater than that of the end portion 67. It will be understood that the

beads 66, disclosed in Fig. 6, are expanded in the tube 66 in the same manner as the beads 21 disclosed in Fig. 2 are formed.

Another advantage of assembling baffles on tubes, according to the present invention, is that in the event that a tube upon which a baffle is to be assembled is slightly out of straight alignment, the ridge for supporting the baffle may be formed so as to be concentric with the desired position of the outer periphery of the baffle, notwithstanding the fact that it may not be concentric with the tube in which it is formed. This feature of the invention is illustrated in Fig. 7, wherein a tube 70 is provided with a ridge 71, not concentric with the tube 70 and supporting a baffle 72. The eccentricity of the ridge 71 is disclosed by comparing the dimensions x and y , the dimension x being smaller than the dimension y . It will be clear that the eccentricity of the ridge 71 is due to the fact that the quill and mandrel supporting the expanding dies for forming the ridge 71 is sufficiently rigid to make the ridge 71 concentric with it, notwithstanding any eccentricity of the tube 70 with respect to the quill and mandrel. The eccentric ridge 70 may be produced either when a substantial ridge, such as the ridge 66, disclosed in Fig. 6, is produced, or when a negligible ridge, such as that disclosed in association with the beads 66 of Fig. 6, is produced. In either case the baffles secured will be in align- 30

ment to enable telescopic reception of an outer tube notwithstanding any irregularity of the inner tube to which the baffles are secured.

Having thus described my invention, what I desire to secure by Letters Patent and claim is:

- 5 1. The method of providing a baffle between an inner and an outer tube of substantially different diameters which comprises crimping the outer tube to provide an inwardly extending annular ring of less diameter than the tube, disposing said inner tube in said outer tube, and expanding a portion of the inner tube opposite said inwardly extending annular ring into peripheral engagement therewith by subjecting said tube portion to a radially outwardly expanding force, whereby said inwardly and outwardly extending tube portions comprise a baffle between said tubes.
- 10 2. In the manufacture of mufflers, the method of providing a baffle between an inner and an outer tube of substantially different diameters which comprises providing an outer tube having a portion thereof of less diameter than the tube itself, disposing the inner tube within the outer tube, and expanding a portion of the inner tube 20 into peripheral engagement with said portion of said outer tube by subjecting said tube portion to a radially outwardly expanding force, whereby said inwardly and outwardly extending tube portions comprise a baffle between said tubes.
